Primary Examiner — Lauren D McVey

(57) **CLAIM**

The ornamental design for the baseplate of a modular equipment for distribution of electric power and data signals, as shown and described.

DESCRIPTION

FIG. 1.1: Perspective top view of a baseplate of a modular equipment for distribution of electric power and data signals;

FIG. 1.2: Perspective rear view of the baseplate;

FIG. 1.3: Right view of the baseplate;

FIG. 1.4: Front view of the baseplate;

FIG. 1.5: Back view of the baseplate;

FIG. 1.6: Top view of the baseplate;

FIG. 1.7: Rear view of the baseplate;

FIG. 1.8: Right view of the baseplate turned on the rear.

(Continued)

The broken lines in the drawings are directed to portions of the article which form no part of the claimed design.

1 Claim, 8 Drawing Sheets
